UNITED STATES PATENT OFFICE.

PETER E. MALMSTROM, OF NEW YORK, N. Y.

DESIGN FOR A BOTTLE.

SPECIFICATION forming part of Design No. 34,896, dated August 6, 1901.

Application filed June 15, 1901. Serial No. 64,759. Term of patent 14 years.

To all whom it may concern:

Be it known that I, PETER E. MALMSTROM, a citizen of the United States, and a resident of the city of New York, borough of Manhattan, county and State of New York, have invented and produced a new and original Design for Bottles and Similar Articles, of which the following is a specification.

My invention relates to a new and original design for a bottle or similar article; and it consists in the shape and configuration substantially as herein shown and described.

In the drawings forming part of this specification, Figure 1 is a side elevation, and Fig. 2 is a top plan view of the bottle.

At 1 is the body of the bottle, 2 the neck, and 3 the base. The base has an annular flange 4 and an inwardly and upwardly curved or arched bottom 5. The neck is very short as compared with the length of the bottle, is cylindrical, and has the circumferential enlargements 6 7, the upper one being sharper and of less dimension than the lower one.

The body of the bottle is of a distorted

elliptical or oval form, it being circular in cross-section throughout its length and its outline being made up of a number of segments of different radius.

By reference to Fig. 1 it will be noted that from the base of the bottle the outline is made up of one segment extending from *a* to approximately *b*, from *b* to *c* a further segment, from *c* to *d* a further segment, and from *d* to the point where the curve of the bottle merges into the neck, as *e*, another segment, all the segments having a different radius. The radius of the intermediate segments between the points *b d* are very long, which gives the bottle a very flat appearance between those points.

Having described my invention, I claim—

The design for a bottle or similar article substantially as herein shown and described.

Signed at the city, county, and State of New York this 14th day of June, 1901.

PETER E. MALMSTROM.
